(57) **CLAIM**

The ornamental design for a laparoscopic apparatus, as shown and described.

DESCRIPTION

FIG. 1 is a perspective view of a laparoscopic apparatus; FIG. 2 is a plan view of the laparoscopic apparatus of FIG. 1; FIG. 3 is a side view of the laparoscopic apparatus of FIG. 1; FIG. 4 is an enlarged first end view of the laparoscopic apparatus of FIG. 1; and,

FIG. 5 is an enlarged second end view of the laparoscopic apparatus of FIG. 1.

The broken lines shown are included for the purpose of illustrating portions of the laparoscopic apparatus that form no part of the claimed design.
